(57) **CLAIM**

The ornamental design for a storage container shelf, as shown and described.

DESCRIPTION

FIG. 1 is a top perspective view of a storage container shelf showing my new design with environment shown in broken lines;

FIG. 2 is a top perspective view of the storage container shelf;

FIG. 3 is front view thereof;

FIG. 4 is a rear view thereof;

FIG. 5 is a left side view with the right side being a mirror image thereof;

FIG. 6 is top view thereof; and,

FIG. 7 is a bottom view thereof.

The broken lines shown are environmental only and form no part of the claimed design.
